[57] ABSTRACT

A crop cutting apparatus having an elongated cutter-

bar, a plurality of guards, and reciprocating knife disposed in the usual arrangement wherein cylindrical cup-like retainer members are mounted by the guard mounting bolts to the top side of the cutterbar. A hold down clip slips over the retainer members and has a rearward portion contacting the cutterbar, a medial portion displaced from the cutterbar, and a forward portion including a horizontal surface acting against the knife and a vertical surface acting against the front side of the knife back. A single tie down bolt disposed between the retainer cups adjustably hold the clip in position to resist upward movements of the knife assembly.
